FILM DEVELOPING APPARATUS

Carl L. Horner, Bellevue, Pa., assignor of one-half
to Robert D. Kreider, Mauch Chunk, Pa.

Application June 26, 1940, Serial No. 342,565

3 Claims. (Cl. 95—90)

This invention relates to means for use in developing and fixing photographic films and is designed primarily for handling the film outside the dark room after it has once been placed in the device, without danger of being exposed to light.

Another object is to provide a new and novel form of tank for receiving a film holder and a treatment liquid, it being possible to supply liquid to and remove it from the tank while the film is located therein and without permitting the film to become light-struck.

A further object is to provide a closure for the tank which serves both to exclude light and support the film holder.

A still further object is to provide a film holder of simple construction in which a length of film can be placed readily, this holder serving to hold the film during the several steps of developing, fixing, washing and drying, so that it need be handled solely while being placed initially in the holder and while being removed after drying.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing—

Figure 1 is a vertical transverse section through the tank with the film holder shown in elevation therein, parts being broken away.

Figure 2 is a section on line 2—2, Figure 1.

Figure 3 is a section on line 3—3, Figure 1.

Figure 4 is a section on line 4—4, Figure 1.

Referring to the figures by characters of reference, T designates a tank formed of any suitable material which will not be affected by film treatment liquids. It is preferably rectangular and proportioned to receive a holder in which a flat strip of film has been placed. The open top of the tank has its front and back walls 1 extended along upwardly diverging planes as at 2. Thus they cooperate with the parallel side walls 3 to form a funnel-like inlet 4.

The bottom 5 of the tank has a drain opening 6 normally closed by a removable plug 7 of rubber or the like and at the top of one of the inclined walls 2 there can be provided a pivotally 55

mounted ring 8 by which the tank can be suspended from a hook or the like.

At points near the inlet 4 the walls 1 are formed with zig-zag grooves G pressed outwardly 5 thereinto and substantially parallel, the upper end portions 9 of each groove being located well above the lower end portion 10.

Removably mounted in the tank is a holder H. This includes a plug 11 preferably of soft 10 rubber proportioned to fit snugly in the upper portion of the tank. It is adapted to bridge the intermediate portion of the grooves G so that only the end portions thereof are left uncovered, the lower ends being below the plug and the 15 upper ends above the plug. The plug has slots 12 in its ends and secured to and extending upwardly from the plug is a stem 13 which can be provided with an eye 14 or the like.

The plug, when in closing position, engages a seat 15 which can be formed of upwardly inclined strips of material joined at their lower edges to the walls 1 and 3 while its free upper edges engage the seated plug and are adapted to press thereinto to form a seal. The grooves 20 G extend between these strips.

Oppositely disposed channelled members 16 are seated removably at their upper ends in the slots 12 and are joined near their ends by cross rods 17, thus forming a rigid frame. These members 30 16 are spaced apart to receive the side edges of a flat strip of film and, to facilitate insertion and removal of the film, the front wall of each channelled member 16 is removed at its upper end to provide inlets 18 for the endwise insertion of the film.

While the device is in a dark room, the film to be developed is inserted endwise into the members 16 so as to lie flat therebetween. The complete holder H, including plug 11 and the frame 40 formed by members 16 and 17, is then inserted into the tank with the plug engaging seat 15. The tank with the enclosed film can then be taken from the dark room and the developing fluid poured into the funnel like inlet 4. From this it will drain through grooves G into that portion of the tank below the plug. Thus the supported film will be submerged. After the development has been completed the tank can be partly inverted and the liquid drained therefrom. Thereafter the washing and fixing fluids can be poured into and removed from the tank in the manner described and in proper succession, the final washing being effected by removing plug 7 and allowing water to flow freely through the tank. Finally the holder H is removed, thus

withdrawing the film from the tank and it can then be suspended by stem 13 from a hook or the like until the film is dry. The film thereafter is removed from the members 16 by sliding it upwardly through the inlets 17 and is then ready for printing.

It will be noted that the zig-zag grooves exclude light rays at all times during the treatment of the film so that the only time a dark room is necessary is while the film is being placed in position in the tank.

The space above the closed plug 11 can be used to measure the approximate amount of liquid to be delivered into the tank.

What is claimed is:

1. Apparatus of the class described including a tank having an inlet and zig-zag grooves in opposed walls below the inlet, a removable plug seated in the inlet and bridging intermediate portions of the grooves, and means suspended from the plug for engaging and holding the edge portions of a film.

2. Apparatus of the class described including a

5 tank, a seat therein, a measuring inlet portion on the tank above the seat, there being grooves in opposed walls of the tank extending above and below the seat and having offset end and intermediate portions, a plug removably engaging the grooves, and a film-engaging frame depending from the plug.

10 3. Apparatus of the class described including a tank, a seat therein, a measuring inlet portion on the tank above the seat, there being grooves in opposed walls of the tank extending above and below the seat and having offset end and intermediate portions, a plug removably engaging the 15 seat and bridging intermediate portions of the grooves, and a film-engaging frame depending from the plug, said frame including opposed connected channeled members each having a portion of its wall removed to form a film inlet, 20 the upper ends of the members being removably seated in the ends of the plug.

CARL L. HORNER.
